CLAIM

The ornamental design for a harness for a personal rescue device, as shown and described.

DESCRIPTION

FIG. 1 is a front perspective view of a harness for a personal rescue device at a spread out position;

FIG. 2 is a top view of the harness shown in FIG. 1 at a spread out position;

FIG. 3 is a bottom view of the harness shown in FIG. 1 at a spread out position;

FIG. 4 is a left side elevational view of the harness shown in FIG. 1 at a spread out position;

FIG. 5 is a right side elevational view of the harness shown in FIG. 1 at a spread out position;

FIG. 6 is a front elevational view of the harness shown in FIG. 1 at a spread out position;

FIG. 7 is a rear elevational view of the harness shown in FIG. 1 at a spread out position;

FIG. 8 is a rear perspective view of the harness shown in FIG. 1 at a buckled position;

FIG. 9 is a top view of the harness shown in FIG. 1 at a buckled position;

FIG. 10 is a bottom view of the harness shown in FIG. 1 at a buckled position;

FIG. 11 is a right side elevational view of the harness shown in FIG. 1 at a buckled position;

FIG. 12 is a left side elevational view of the harness shown in FIG. 1 at a buckled position;

FIG. 13 is a front elevational view of the harness shown in FIG. 1 at a buckled position; and,

FIG. 14 is a rear side elevational view of the harness shown in FIG. 1 at a buckled position.

The broken lines depict portions of the harness for a personal rescue device that form no part of the claimed design.

1 Claim, 14 Drawing Sheets
